US00D646402S

(12) **United States Design Patent**
Mugge

(10) **Patent No.:** **US D646,402 S**
(45) **Date of Patent:** **** Oct. 4, 2011**

(54) **MOLDED SURFACE OF A CONCRETE PRODUCT**

(75) Inventor: **Jimmie L. Mugge**, Inver Grove Heights, MN (US)

(73) Assignee: **Anchor Wall Systems, Inc.**, Minnetonka, MN (US)

(**) Term: **14 Years**

(21) Appl. No.: **29/373,128**

(22) Filed: **Mar. 4, 2011**

CLAIM

The ornamental design for a molded surface of a concrete product, as shown and described.

DESCRIPTION

FIG. 1 is a perspective view of a molded surface of a concrete product;

FIG. 2 is a front elevational view thereof;

FIG. 3 is a top view thereof;

FIG. 4 is a bottom view thereof;

FIG. 5 is a right side view thereof; and,

FIG. 6 is a left side view thereof.

The broken lines in the drawing views are included for the purpose of illustrating portions of the molded surface of a concrete product that form no part of the claimed design.

1 Claim, 6 Drawing Sheets
